Louis Gravine, Albany, N.Y. assignor to Jesse C. Potts, Albany, N.Y.
Letters Patent (Design No. 57) dated 10th July 1846.

The Schedule referred to in these Letters Patent and making
part of the same.

To all whom it may concern:

Be it known that I, Louis Gravine of Albany in
the County of Albany and State of New York, have invented or produced a

a new ornamental design for an ornamental cooking stove, and I do hereby declare that the subjoined drawings are full and accurate representation thereof, — Fig. 1st being a general perspective view, and Fig. 2, a view of the side, (both sides being alike) upon a larger scale to show more clearly the detail of ornament.

Fig. 3 is a view of one half the front, the remaining portion being of course similar and symmetrical.

What I claim as my invention and desire to secure by this Patent is, the combination and arrangement of ornamental figures represented in the accompanying drawings, forming a design for an ornamental cooking stove.
